S. Silliman,

Washing Machine,

Patented Feb. 3, 1830.

Samuel Hillman

Letters Patent.

The schedule referred to in these Letters Patent are making part of the same containing a description in the words of the said Samuel Hillman himself of his improvement in the machine for washing clothes, called the vibrating Washing Machine -

To all whom these presents shall come greeting,
Be it known that I, Samuel Hillman of Saybrook in the County of Middlesex and State of Connecticut, have invented, constructed, made, and applied to me a new and useful improvement in the washing Machine, called the vibrating Washing Machine, the schedule and Specification of which is as follows, viz -

A rectangular washing tub three feet long, one & a half feet wide and fourteen inches high, standing on four legs or feet of sufficient height for convenience - one end an inch lower than the other, with a faucet or plug at the lowermost end in the bottom to draw off the water - two feet three or four inches wide & an inch thick erected one on each side of the tub, perpendicular from the ends, well bound on the outside by screws or otherwise with a hole near the upper end of an inch in diameter & about four feet and a half above the bottom of the tub to receive the post or shaft.

The shaft has an arbor, on each end fitted to the hole in the posts with a shoulder & a nut of hard wood screwed or otherwise fastened on in the way to keep the post to the shoulders. Through the shaft a little further the shoulders are two mortises of an inch square the which the vibrating frame slides up and down. The vibrating frame is made of hard wood and consists of two long pieces made of beams no such thick one about nine inches wide at the base and 21 inches long from the upper end to the edge of the mortises in the shaft. The upper end of the frame is made about seven inches long.

The form of the cabin conforms to the shape of the hull, frame, the
deck board is a loose floor filling the inside of the hull, raised from
the bottom and secured by placing two sets made of boards one inch
thick one on each side of the tub - the upper one being made circular
in which are nailed or otherwise secured boards fitted on the upper
deck covering, corfous of the tub are perforated with holes in the
planks, three eights of an inch in diameter, 4 two inches apart.

The wash board at the middle is about one and a half inch from the bottom of the tub & rises towards the ends of the tub to the edges of the vibrating frame. It may be taken out at pleasure.

In the operation of the machine, the clothes to be washed are placed upon the wash board - water is put into the tub sufficient to make the washboard float. the rollers are then made to pass over the clothes with the weight of the vibrating frame upon them.

The rollers may be increased in number or diminished & the machine may be enlarged or diminished according to the amount of working required. The washboard is taken from the tank, preparatory to removal from the bottom - the rollers attached to the washboard.

plane with its tail is set in the same position
as will the tail of the plane in the position of the left
wing with the hands placed on the sides, and closed arm-in-
the-hands position of the right wing.
